MARBLE GAME

Frederick H. King, Detroit, Mich.

Application January 12, 1935, Serial No. 1,453

8 Claims. (Cl. 273—127)

This invention relates to marble games, and particularly to marble games comprising a target at which marbles may be shot or otherwise propelled.

5 An object of the invention is to provide a target for marbles or the like comprising a plate formed at its lower edge with a row of spaced openings through which a marble may pass, said openings varying in width to vary the facility 10 with which a marble may pass through the different openings.

Another object is to provide a frame for mounting the marble target, the parts of which may be readily disassembled from each other and from 15 the target.

A further object is to position a holder for a so-called king marble at the rear of the described target, and to provide said holder with a trip arm serving to release the king marble when 20 struck by a shot marble.

A further object is to adapt the king marble holder to be easily detachably secured to the frame of the device in rearward alignment with any of the target openings.

25 These and various other objects the invention attains by the construction hereinafter described, and illustrated in the accompanying drawing, wherein:

Fig. 1 is a perspective view of the target with 30 its frame and the king marble holder.

Fig. 2 is a fragmentary perspective view showing how the target plate and the parts of the frame are fitted together.

Fig. 3 is a sectional view of the king marble 35 holder and the frame bar carrying the same.

In these views, the reference character 1 designates a horizontally elongated target plate which may be formed of fibre board, and is adapted to be vertically mounted upon or adjacent to a floor, and is formed with a row of openings 2, 3, 4, 5, 40 and 6, upwardly arched from its lower edge and spaced lengthwise of said edge. Said openings vary slightly in width, the narrowest opening 2 being preferably midway between the ends of the 45 plate, the widths of the openings increasing preferably in the order indicated by the series 2, 3, 4, 5, 6. Adjacent to and preferably above each of said openings, a score number is marked upon the front of the plate, the score numbers corresponding to the respective openings 2, 3, 4, 5, and 6, being respectively 10, 8, 6, 4, and 2. Thus it is seen that the smallest opening provides for the largest score, and that the score decreases as the width of the opening increases.

55 The plate 1 is notched at its ends and in prox-

imity to its lower edge as indicated at 8, to engage the forward portions of a pair of frame bars 9, which form the sides of the target frame, said bars being downwardly notched as indicated at 10, to accommodate the target plate. The side bars are held properly spaced by a rear frame bar 11, the end portions of which are upwardly notched as indicated at 12 to engage in downward notches 13 formed in the rear end portions of the side bars. Thus it is seen that the target 10 plate and the parts of the frame may be quickly 15 and easily assembled in operative relation or disassembled, and are adapted to be quite compactly arranged for boxing for shipment. It is to be noted that the side bars project sufficiently forward beyond the target plate to prevent lateral deflection of marbles encountering the front face of such plate.

Some distance rearwardly of the target plate and preferably upon the rear bar 11 of the frame, 20 it is preferred to mount a king marble holder formed preferably of sheet metal stampings. Thus, a sheet metal plate 14 adapted to seat against the front face of the bar 11 carries an integral hook 15 for snugly straddling said bar, 25 and is further integrally formed with a pair of spaced parallel forwardly projecting arms 16 to mount the king marble receiver 17. The latter consists of a U-shaped sheet metal member mounted between said arms and formed with a pair of tongues 18 insertable in opposed openings in the front of said arms to pivotally mount the receiver. The rear portion of the receiver is 30 rearwardly hooked as indicated at 19, to normally loosely engage the hook 15 to thereby limit the 35 downward rocking of the receiver. A trip arm 20 projects integrally downward from the front portion of the receiver at a forward inclination, terminating adjacent to the floor or other surface supporting the frame.

In use of the described game, the players shoot or roll marbles at the target from some definite position suitably forwardly spaced from the target, the endeavor being to shoot the marble through a selected one of the openings 2, 3, 4, 5, 45 and 6. Delivery of a marble through any of said openings accrues for the player a score equal to the number marked adjacent to such opening. If a marble so delivered further encounters the trip arm 20 and thereby dislodges the king marble (see dash line showing of Fig. 3), the score 50 accruing from the shot is doubled. If the king marble rolls forwardly and passes through one of the openings 2, 3, 4, 5, 6, the shot scores double 55

the score number of the opening through which his marble was delivered, and additionally the score number of the opening through which the king marble escaped. If the king marble escapes 5 forwardly through the same opening by which a played marble passes through the target plate, the resulting score is three times the score number of such opening. The first player whose 10 accumulated score reaches some arbitrary total as for example, three hundred, may be considered the winner.

The king marble is preferably rearwardly aligned with the opening 2 of the target plate, but said holder may be slid along the frame bar 15 11 to align it with any desired opening of the target plate.

It is to be noted that the frame 9, 11, forms 20 with the target plate an enclosure which may easily accommodate a considerable number of marbles. Thus, if preferred, each player may shoot a suitable predetermined number of marbles before yielding place to another, such marbles as enter said enclosure accumulating 25 therein.

25 It is further to be noted that the trip arm in dislodging the king marble from its holder, imposes on such marble a forward impetus such as will ordinarily cause it to either encounter the target plate or pass through one of the openings 30 of such plate.

The described game is simple and inexpensive and will serve to amuse adults as well as children.

The invention is presented as including all such modifications and changes as come within the 35 scope of the following claims.

What I claim is:

1. In a marble target, a support engageable with a surface on which marbles may be propelled, a member carried by said support and 40 formed with a pair of substantially parallel spaced arms, a receiver for a marble pivoted between and transversely of said arms, and a trip arm for dislodging said marble and projecting downwardly from said receiver and into a proximity to said 45 surface, adapting such arm for actuation by a marble propelled on said surface.

2. In a marble target, a sheet metal stamping engageable with a support and formed with a pair of spaced substantially parallel arms forwardly 50 projecting from said support, an approximately U-shaped receiver for a marble pivoted upon and between the front portions of said arms, and having a rear portion resting normally on said support, and a trip arm downwardly projecting from 55 the forward portion of said receiver for actuation by another marble, and adapted, on actuation, to release the marble from the receiver.

3. In a marble target, a support engageable with a surface on which marbles may be propelled, a pair of spaced arms similarly projecting from said support, a marble receiver pivoted 60 upon the support between said arms and coacting therewith to normally retain a marble, a trip arm downwardly projecting from the receiver for actu-

ation by another marble, and adapted to release the supported marble upon such actuation.

4. A marble game comprising a target plate 5 formed with a row of marble passages upwardly opening from its lower edge, a frame comprising a pair of side bars rearwardly extending from the ends of the target plate and holding said plate substantially upright and a cross bar connecting the side bars and forming therewith and with the target plate a marble-receiving enclosure, and a device adjustably mounted upon 10 said cross bar for registration with any of the target plate passages, said device comprising a marble support, and means operatively associated with such support for tripping a marble therefrom under impact of another marble delivered through one of said passages.

5. A marble target comprising a marble receiver pivoted for upward actuation to dislodge a marble therefrom, an arm downwardly projecting 20 from such receiver for effecting marble-releasing actuation of the receiver, and a member pivotally mounting the receiver and comprising portions laterally adjacent to the receiver to assist in normally retaining a marble thereupon.

6. In a marble game, a target plate having a 25 row of marble passages upwardly opening from its lower edge, a frame attached to the target plate and forming a marble-receiving enclosure rearwardly of such plate, a marble support carried by 30 said frame in a rearwardly spaced relation to the target plate, and means operatively associated with such support for dislodging a marble therefrom under impact of another marble delivered through one of said passages, and for impelling 35 the dislodged marble forwardly toward the target plate, whereby the score may be varied accordingly as a marble is passed either rearwardly or forwardly through the passages.

7. In a marble target, the combination with a 40 member comprising a back and a pair of spaced arms forwardly projecting from said back, of a member pivoted upon and between said arms, forming a seat for a marble and formed rearwardly of such seat with a stop engageable with 45 said back to establish a normal position of said seat, and formed forwardly of said seat with a downwardly projecting trip arm for tilting said seat upwardly to dislodge a seated marble.

8. A marble game comprising a target plate 50 formed with a row of marble passages, a frame comprising a pair of side bars rearwardly extending from the ends of the target plate and holding said plate substantially upright and a cross bar connecting the side bars and forming therewith and with the target plate a marble-receiving enclosure, and a device adjustably mounted upon said cross bar for substantial registration with any of the target plate passages, 55 said device comprising a marble support, and means operatively associated with such support for tripping a marble therefrom under impact of another marble delivered through one of said passages.

FREDERICK H. KING.
